UNITED STATES PATENT OFFICE

2,172,947

TELEPHONE SYSTEM

Reginald Taylor and George Thomas Baker, Liverpool, England, assignors to Associated Telephone and Telegraph Company, Chicago, Ill., a corporation of Delaware

Application January 29, 1936, Serial No. 61,289
In Great Britain February 6, 1935

6 Claims. (Cl. 179—18)

The present invention relates to improvements in automatic or semi-automatic telephone systems and the particular object of the invention is to provide an improved arrangement for insuring efficient use of the bank contacts of the switches employed in such systems. The invention has particular application in connection with final selector switches whether serving P. B. X. groups of lines or single lines or both, although it is not limited thereto, and by its assistance the establishment and the distribution of the lines in P. B. X. groups is greatly facilitated. For example, if it is required to extend a P. B. X. group, adjacent sets of spare contacts are not now essential and it is possible by means of the invention to group together spare contacts in indiscriminate positions and associate them with any desired P. B. X. group of lines.

According to one of the features of the invention if the selector switch encounters a busy condition a signal is transmitted to apparatus common to a number of said switches and the further control of the switch including its resetting on to a different line leading in the same direction or the transmission of a busy signal if no such line is available is effected by the common apparatus. By this means the changes in existing final selectors are reduced to a minimum.

According to a further feature of the invention on a busy line or busy group of lines being encountered means are provided adapted to respond to such busy condition to effect the release and resetting of the switch on to an idle line having access to the same subscriber connected in another part of the switch bank or to give a busy signal if there is no such line available.

According to another feature of the invention, in order to enable the switch to be reset in the event of the line or group of lines first tested being found busy a switch having access to a number of different groups of final selector switches is adapted to be taken into use such switch having associated therewith, means for indicating the particular line or group of lines being tested, means for ascertaining if there is an idle line leading to the required subscriber and means for controlling the resetting of the final selector switch onto such idle line if no idle line is available causing a busy signal to be given.

According to yet another feature of the invention, in order to enable the switch to be reset in the event of the line or group of lines first tested being found busy, apparatus common to a plurality of final selectors is adapted to be associated therewith said apparatus comprising

means for determining the level on which the switch is resting, means for causing the switch to advance step by step to a predetermined position on the level so as to determine the contact on the level, means for ascertaining if there is an idle line leading to the required subscriber and means for causing the switch to be reset on to such idle line.

The invention will be better understood from the following description of one method of carrying it into effect, reference being had to the accompanying drawings comprising Figs. 1—6 of which Fig. 1 is a trunking diagram, while Figs. 2—5 when assembled as shown in Fig. 6 show the circuit connections.

Referring now to the trunking diagram, FS represents a final selector to which the facilities of group extension are provided. GP represents common group pilot apparatus which conveniently may be provided in duplicate for one hundred final selectors such as FS. With the group pilot apparatus GP there is associated a finder switch F, a marking switch M, both adapted to move in two directions, and one or more auxiliary line selecting switches ALH adapted to move in a single direction, and an impulse control switch S.

The operation is briefly as follows:

When the final selector FS encounters a busy condition on any line whatever a start circuit is completed to the common group pilot apparatus GP. This causes the finder F to hunt to find the final selector in question. When this is done the marker switch M begins to operate, firstly to the level on which the final selector FS is resting and secondly the rotary magnets of the two switches will step in unison until wipers of the final selector FS have reached a particular position—say the eleventh, when the movement of both switches ceases and the marker switch M rests on contacts corresponding to the contacts on which the final selector has encountered the busy condition. If this contact has no auxiliary lines associated with it the group pilot apparatus is at once released and the final selector is caused to send a busy tone to the calling subscriber. If however, the contact in question is one of a P. B. X. group which has auxiliary lines, the final selector is at once released and a start circuit is extended to the auxiliary line selecting switch ALH which hunts first of all to find the first line in the auxiliary group associated with the line or P. B. X. group selected and if that line is busy and is not the only line in the auxiliary group it will hunt to find an idle line in the auxiliary group. On finding a free line, the line is imme-

dately busied. The final selector is then directionally set as regards its vertical and rotary movements by the impulse sending switch S, which in turn is controlled in accordance with the particular line selected by the switch ALH. The switching relay in the final selector is then operated to switch through to the selected line and the group pilot apparatus is restored for further use.

10 It will be understood that the invention may be applied to existing types of final selector switches, whether those having access to individual lines only or to P. B. X. groups of lines only or to both individual lines and P. B. X. groups of lines, as well as being incorporated in the design of new circuits.

15 Referring now to the operation of the circuit, it should be explained that only the elements of a typical P. B. X. final selector necessary for 20 the understanding of the invention are shown and these will be found to the left of the vertical dotted line in Figs. 2 and 4. With the exception of the busy condition the operation of the P. B. X. final selector takes place in the usual 25 manner and the circuit modifications necessary for adapting the busy condition to start up the group pilot apparatus will be fully appreciated from the description which follows.

30 When a P. B. X. final selector encounters a busy condition its relay G operates and at contacts g_1 or g_2 connects resistance battery respectively to the odd or even level start conductor OLS or ELS leading to the group pilot apparatus, and at the same time at contact g_3 or g_4 extends a marking battery to the vertical 35 bank AWF of the finder to indicate the level in which the final selector is located. The dotted connection shunting contact g_3 applies only to the 0 level. The provision of odd and even 40 level start conductors leading to the main and duplicate group pilot apparatus respectively evens up the load on the equipment and enables one to act as an auxiliary to the other in the event of a fault. The connection of resistance 45 battery to the odd level start conductor causes relay SA to operate in series with relay SB which is marginal and only operates when two or more final selectors located on odd finder levels encounter a busy condition simultaneously. In 50 this case the function of relay SB is to extend the start circuit to the duplicate group pilot apparatus so that both finders are taken into use and the waiting time is reduced. Relay SA at armature sa_1 operates the start relay ST Fig. 5 55 which in turn at armature st_1 Fig. 4 completes a self-interrupted driving circuit to the vertical magnet VF of the finder. The finder accordingly steps its wipers in search of the marked 60 level and when this is found a circuit is completed over the vertical bank AWF for operating relay LK over both its windings in series. Relay LK thereupon at armature lk_1 disconnects the driving circuit to the vertical magnet and completes a locking circuit for LK over its 65 left hand winding which is sufficiently low in resistance to mark the level selected as busy to the other finders. At armature lk_2 the following self interrupted driving circuit is completed to the rotary magnet RF of the finder switch: 70 earth at the interrupter springs cm Fig. 2, wiper S1 and first bank contact of the sender switch, interrupter springs rm , of the marker switch, armature rs_3 , interrupter springs rf of the finder, off normal springs NM_1 of the marker, armature co_3 , off normal springs NF_1 of the finder, 75

5 armature lk_2 to the rotary magnet RF. The wipers F_1 to F_8 of the finder are therefore rotated in search of the final selector in question and when this is found earth from the G relay circuit is picked up by wiper F_8 of the finder and causes the comparatively high resistance relay RS to operate in series with magnet RF. The resistance YF in parallel with relay RS is of a comparatively low value and serves to check the operation of the magnet. The metal rectifier 10 MRB prevents earth from the magnet circuit feeding back to relay RS and wiper F_8 . Relays RS in operating at armature rs_1 disconnects the resistance YF , at armatures rs_2 and rs_3 extends potential through relay VT and the wiper F_7 of the finder to mark the vertical bank AWP of the 15 final selector, at armature rs_4 extends a corresponding marking to the vertical bank AWM of the marker switch, at armature rs_5 , Fig. 2 connects the high resistance relay HR to wiper F_2 20 of the finder so that it operates in series with the switching relay of the final selector which is not energised at this time, and finally at armature rs_7 Fig. 2 completes a self-interrupted driving circuit to the vertical magnet VM of the 25 marker switch which thereupon commences to hunt vertically. It should be explained here that the vertical bank AWM of the marker switch, Fig. 4, is multiplied with the vertical banks AWP of all final selectors served by the 30 group pilot in question so that it will be understood that the marking potential applied to relay VT is extended over the vertical bank of the final selector to mark a particular level in the vertical bank of the marker switch corresponding to the level on which the wipers of the final selector are resting. Accordingly when the wipers of the marker switch are raised to the marked level, relay VT operates and at armature vt_1 , Fig. 2, opens the driving circuit to the 35 magnet VM and removes a short circuit from the high resistance relay VTR which thereupon operates in series with the magnet, the latter however not energising in this circuit. Since the marker switches of both group pilots may be 40 hunting at the same time on simultaneous calls, it is important to ensure that the respective relays VT shall be operated only from their own marking switches and to this end the vertical wiper or marker switch No. 1 is connected to 45 earth and the vertical wiper of marker No. 2 is connected to battery as indicated by the alternative connections shown in the drawings. Furthermore, as VT relays are each connected to the centre point of a potentiometer resistance 50 it is necessary to include metal rectifiers MRA in their circuit connected up in opposite senses so that there shall be no danger of a marker switch stopping on a level marked via the finder associated with the other marker switch. 55

60 There is also the possibility of both VT relays being connected together due to the finders of both group pilots being set to corresponding levels. In these circumstances the rectifiers are obviously without effect but as both VT relays 65 present the same potential, no current flows and consequently no false operation results.

65 Relay HR in operating at armature hr_1 completes a local holding circuit for relay ST, Fig. 5, at armature hr_2 disconnects relays SA and SB and 70 at armature hr_3 provides a local holding circuit for relay RS. Returning to the operation of relay VTR, at armature vt_1 a further point is opened in the short circuit path about its winding, at armature vt_2 , Fig. 4, the rotary magnet 75

RM of the marker is energised and at armature *vtr4* earth is connected to wiper *F6* of the finder to energise the rotary magnet *IRM* of the final selector. When the rotary magnet *RM* fully energises the interrupter springs *rm* open and disconnect the short circuiting earth from one side of the winding of relay *GA*, and further when the rotary magnet *IRM* of the final selector fully operates the associated springs *r* close and connect earth to the wiper and bank *F5* of the finder to operate relay *GA* over one winding in series with resistances *YA* and *YB*. Relay *GA* thereupon at armature *ga2* and *ga3* opens the circuits to both rotary magnets which accordingly release. Interaction therefore takes place between the final selector and marker rotary magnets and relay *GA* so that when the wipers of the final selector come into their 11th position the wipers of the marker switch will have been moved to a complementary position corresponding to the busy contact in question.

In the 11th position cam springs *S* in the final selector operate and connect earth over bank and wiper *F4* of the finder to hold relay *GA* in series with relay *EC* which also operates. Relay *GA* in holding prevents further interaction between the rotary magnets while relay *EC* at armature *ec2* and *ec3* connects relays *EL* and *CO* respectively to the wiper *F1* of the finder. It should be explained here that all contacts in the bank *F1* of the finder corresponding to final selectors serving the same hundred group of lines are commoned together and connected to a particular wiper of the marker switch as indicated in the drawings and it will be obvious therefore that, while wiper *F1* of the finder selects the correct 100 line group, the wiper of the marker switch selects the contact in that hundred line group which has been selected and found busy by the final selector.

If the contact in question has no auxiliary lines associated with it, it is jumpered direct to earth which is extended over the wiper of the marker switch and the wiper of the finder to operate relay *CO*. Relay *CO* locks over its armature *co1*, and at armature *co2* short circuits the high resistance winding of relay *HR* to bring about the switching of relay *H* in the final selector. The operation of relay *H* with the wipers in the 11th position causes busy tone to be extended to the calling subscriber and relay *HR* is short circuited and released by the locking armature of relay *H*. Relay *HR* in turn releases relays *ST* and *RS* at armatures *hr1* and *hr3* respectively. On the release of armature *rs3* a self-interrupted driving circuit is completed to the rotary magnet *RM* of the marker switch which accordingly rotates its wipers to the end of the bank and restores to normal whereupon the circuit is opened at the off normal springs *NM1* and transferred to the rotary magnet *RF* of the finder. The finder therefore in turn rotates its wipers to the end of the bank and restores to normal and the circuit is opened at off normal springs *NF1*. During the homing operations of the respective switches in the group pilot apparatus a circuit is completed over off normal springs *NM2* or *NF2* and the resting armature *st5* for operating relay *RG*, Fig. 5, which provides a guarded release condition by opening the operating circuit to relays *SA* and *SB* and temporarily transferring the start circuit to the other group pilot apparatus. Should the switch fail to restore within a reasonable period the continued connection of battery over armature *rg2*, Fig. 5, to the common con-

ductor *13* causes a release alarm to be actuated.

If the line in question has auxiliary lines associated with it, the contact in the marker switch bank will be jumpered to a contact in the bank *ALH4* of the auxiliary line hunter corresponding to the first of the auxiliary group of lines. As the wiper of the marker switch fails to pick up earth under these conditions a short circuit is not presented to the high resistance relay *EL*, Fig. 2, which therefore operates in series with relay *CO* which remains normal. Relay *EL* thereupon locks by way of its armature *el3* in series with the vertical magnet *VM* of the marker switch, at armature *el2* extends earth over the wiper *F1* in the finder and the marker switch wiper selected to mark the first contact of the auxiliary group of lines in the bank *ALH4*, and at armature *el1* extends earth over the low resistance winding of relay *EC* to wiper *F6* of the finder to energise the rotary magnet of the final selector. The final selector therefore steps to its 12th position from which it releases to normal. Relay *EL* at armature *el4*, Fig. 3, completes a self-interrupted driving circuit to the magnet *ALM* of the auxiliary line hunter *ALH* which thereupon rotates its wipers in search of the position marked by the marker switch and corresponding to the first line of the auxiliary group associated with the busy line in question.

When this is found relay *IG* operates when the interrupter springs *alm* open and at armature *ig5* temporarily disconnects the driving magnet *ALM* and at armature *ig1* prepares a circuit for the upper winding of relay *IH* in series with the lower winding of relay *IG* to the wiper and bank *ALH3* which connects with the private normals of the auxiliary lines. If the first line is busy wiper *ALH3* will encounter earth so that relay *IH* does not operate and when the interrupter springs *alm* again close relay *IG* is short circuited and released and the switch *ALH* takes a further step. This action takes place automatically until a free line is found and it will be understood that the group of contacts in the bank *ALH4* corresponding to the auxiliary group of lines are connected together and earthed over the marking circuit in order that relay *IG* may be operated to prepare the test circuit to relay *IH* at each step of the switch *ALH*.

When a free line is found relay *IH* operates from battery supplied by the subscriber's cut-off relay and locks over its lower winding and the make-first armature *ih1*, and at armature *ih2* the upper high resistance winding of relay *IH* is short circuited and relay *IG* now holds over its lower low resistance winding in series with the cut off relay in the called subscriber's line circuit. The line selected is thus guarded and relay *IG* at armature *ig5* holds open the driving circuit to the magnet and at armature *ig4* connects earth to the wipers and banks *ALH5* and *ALH6* to make two markings in the bank *S3* of the sender switch, as determined by the jumping shown in the drawing, to control the generation of a train of impulses necessary directly to set the final selector into engagement with the auxiliary line found by the switch *ALH*. Relay *IH* therefore at armature *ih3* extends earth from the sender switch magnet springs *sm* to the finder wiper *F4* to energise the vertical magnet of the final selector which accordingly raises the wipers one step and at the conclusion of the magnet stroke the springs *v* close and connect earth over the bank and wiper *F5* of the finder to energise the sender switch driving mag-

net SM. The magnet SM therefore prepares for the advancement of the wipers S1 to S3 on to the next set of contacts and at the conclusion of the magnet stroke opens the springs sm thereby de-energising the vertical magnet of the final selector. This action continues automatically until the final selector is raised to the desired level, whereupon wiper S3 of the sender switch encounters the first earthed marking and upon the opening of springs sm relay SS operates in series with the vertical magnet. Relay SS locks over its armatures ss1 and at armature ss3 operates relay SZ which also locks and in turn at armatures ss2 and ss3 transfers the driving circuit from the vertical magnet VM to the rotary magnet RM of the final selector and at the same time short circuits and releases relay SS. When armature ss2 restores to normal the rotary magnet of the final selector now interacts with the driving magnet of the sender switch and when the final selector wipers have been set to the desired contact wiper S3 of the sender switch encounters the second earthed marking. On the opening of the springs sm relay CO now operates in series with the rotary magnet of the final selector and brings about the operation of the H relay to switch the final selector on to the auxiliary line. The final selector now takes over the call and performs its functions in the usual manner while the release of relay HR, following the energisation of the H relay of the final selector initiates the release of the group pilot apparatus which restores for further use.

If the auxiliary line hunter fails to find an idle line, relay BC is operated from wiper and bank ALH2 at the commencement of the second revolution, and at armature bc3 and bc4 makes the position I and II in the bank of the sender switch S. Relay BC also at armature bc2 operates relay IH which locks and causes the sender switch to interact with the final selector as described so that the wipers of the latter are set to the 11th position on the first level. The final selector therefore, transmits busy tone to the calling subscriber in the manner previously described and the group pilot apparatus is released for further use.

In case the final selectors are arranged to serve 200 line groups, relay WS in the group pilot apparatus is operated, under the appropriate conditions, from earth extended over the wiper and bank F3 from the final selector and at armatures ws1 to ws4 changes over the connections to the wipers of the marker switch in order to establish connection with the correct hundred line group.

The delayed alarm relays TA and RG, Fig. 5, are provided for the purpose of supervising the operation of the group pilot apparatus and in case it fails to fulfil its function within a predetermined period of time an alarm is provided and the group pilot in question is switched out of service.

As regards the operation of these relays, it will be remembered that relay ST is operated immediately the group pilot is taken into use and accordingly at its armature st3 connects relay TA to the common conductor extending to the motor driven cam S. The Z cam is also driven on the same shaft as the S cam and the function of these cams is to deliver earth pulses alternately to the common conductors shown at, conveniently, 6 second intervals.

Upon the application of the S pulse relay TA operates and locks over its other winding, at armature ta2 prepares relay RG for the reception

of the Z pulse and at armature ta3 prepares the circuit to conductor 10 extending to the supervisory alarm apparatus. If the group pilot apparatus fails to complete its function within the period allowed relay TA remains operated and upon reception of the Z pulse relay RG is operated and locked in series with relay ST. Relay RG at armature rg2 connects resistance battery to conductor 10 to operate the supervisory alarm apparatus, at armatures rg3 and rg4 connects earth to the common conductors 11 and 12 to operate rack and main exchange alarms, at armature rg5 routes further calls intended for this group pilot to the other group pilot, at armature rg6 opens the busy marking to the vertical bank, at armature rg7 opens the circuit to the vertical magnet of the finder and at armature rg8 Fig. 5 lights the supervisory lamp LP individual to the group pilot apparatus under fault. The exchange attendant is thus notified of the fault condition and by tracing back the various alarms the faulty group pilot is quickly located and the fault attended to.

It should be understood that while the actual final selector circuit referred to is that proposed for use with switches which step on release to the 12th position on a level and then fall in the vertical direction, the invention is also applicable to final selectors of other constructions in which the release takes place by a backward movement along the path over which the wipers were set. Further the invention is not necessarily limited to switches having movement in two directions as it can be equally applied to switches having movement in a single direction. It is also possible by suitable circuit re-arrangement for the 11th step contacts in the various levels to be utilised for auxiliary lines and in these circumstances it will be arranged that the busy circuit is rendered ineffective when the switch is directly set to the 11th position.

We claim:

1. In a telephone system, a final selector switch, a group of lines accessible to said switch, means effective if said switch is set on the first line of said group and said line is found busy for releasing said switch, means for testing the lines of said group to find an idle line, and means for directly reoperating said switch to connect with such idle line.

2. In a telephone system, a plurality of groups of final selectors, each group having access to groups of lines, common means effective whenever any final selector is operated to select a group of lines and finds the first line of the group busy for identifying the operated final selector and the selected group of lines, means for releasing the final selector, means for finding an idle line in the selected group, and means for directly reoperating the final selector to connect with such idle line.

3. In a telephone system, a final selector switch, groups of lines accessible to said switch, means effective if said switch is operated to select a group of lines and finds the first line busy for releasing said switch, means for testing the lines of the selected group to find an idle line, and a sender controlled by said testing means for transmitting impulses to said switch to reoperate it to connect with the idle line.

4. In a telephone system, a plurality of final selectors, groups of lines accessible to said selectors, a finder having access to said selectors, means responsive to a selector being operated to select a group and finding the first line of the

- group busy for operating the said finder to connect with the operated selector, a marker and means for operating it to identify the selected group, a testing switch controlled by said marker to find an idle line in the selected group, means for releasing the operated selector, and a sender controlled by said testing switch to transmit impulses through the finder to the selector after it is released to reoperate it to connect with the idle line.
- 5 5. In a telephone system, a connector switch, a group of lines accessible to said switch, said switch being directly operable to connect with the first line of said group whenever it is idle, means responsive whenever the first line of said group is busy when said switch is directly operated thereto for determining the busy line on which said switch is resting and for restoring said switch to normal, means for finding an idle line in said group of lines and for making such 10 line busy, and means for automatically resetting
- 15
- 20

said switch to connect with the line busied by said last mentioned means.

6. In a telephone system, a connector switch, a group of lines accessible to said switch, said switch being directly operable to connect with the first line of said group whenever it is idle, an auxiliary switch operable to find said connector whenever the first line of said group is busy when said connector switch is directly operated thereto, a marker switch, means controlled by 10 said auxiliary switch for operating said marker switch to find the busy line, a line selecting switch, means controlled by said marker switch for controlling said line selecting switch to find an idle line in said group of lines and for restoring said connector switch to normal, and means controlled by said line selecting switch re-operating said connector switch to connect with the line found by said line selecting switch.

REGINALD TAYLOR.
GEORGE THOMAS BAKER.
